UNITED STATES PATENT OFFICE.

RAYMOND BRUNSWICK, OF PHILADELPHIA, PENNSYLVANIA, ASSIGNOR TO M. RICE CO., OF PHILADELPHIA, PENNSYLVANIA, A CORPORATION OF PENNSYLVANIA.

DESIGN FOR A FLOWER HOLDER.

Application filed May 13, 1927. Serial No. 21954. Term of patent 7 years.

To all whom it may concern:

Be it known that I, RAYMOND BRUNSWICK, a citizen of the United States, residing in Philadelphia, Pennsylvania, have invented a certain new, original, and ornamental Design for a Flower Holder, of which the following is a specification, reference being had to the accompanying drawing, the figure of which is a perspective view of a flower holder illustrating my new design.

I claim:

The ornamental design for a flower holder, substantially as shown.

RAYMOND BRUNSWICK.
